UNITED STATES PATENT OFFICE.

HERMAN SCHLAICH, OF ELMHURST, NEW YORK, ASSIGNOR TO MOTO METER COMPANY, INC., OF LONG ISLAND CITY, NEW YORK, A CORPORATION OF NEW YORK.

RETAINING DEVICE FOR RADIATOR CAPS.

Application filed March 24, 1922, Serial No. 546,437. Renewed July 13, 1928.

This invention relates to retaining devices for radiator caps of automobiles and particularly for caps which are equipped with instruments such as the motor heat indicating instrument now in common use on motor vehicles. Radiator caps when so equipped, offer a temptation to the petty thief, and the general object of this invention is to provide a new and improved retaining device which is simple and rugged in construction, cheap to manufacture, easily applied, and when applied will be efficient for the purpose for which it is intended.

The retaining device hereinafter described in some respects resembles the retaining device which forms the subject of my prior application for patent, Serial No. 377,501, filed April 29, 1920, but contains features which may be considered as improvements thereon. Features disclosed but not claimed herein are claimed in said application Serial No. 377,501.

The invention will be understood from the following description, taken in connection with the accompanying drawing in which Figure 1 is a side elevation of a preferred form of retaining device having the invention embodied therein; Figure 2 is a similar elevation, partly in section, at right angles to Figure 1; Figure 3 is an elevation, partly in section, showing the retaining device of Figures 1 and 2 in use; Figure 4 is a side elevation of one of the parts of the toggle; and Figure 5 is a fragmentary plan view of a portion thereof.

Referring to the drawings, the toggle member is shown as having two parts one of which is a sheet metal channel 6, preferably having the cross-section shown, the sides of said channel being cut at a plurality of points 7 so as to permit the toggle or retaining member to be bent to some such form as that shown in Figure 2, and afterwards restored to the substantially straight form shown in Figure 3 in which its length is preferably at least twice the diameter of the neck of any radiator in which the device is intended to be used. The middle part of the part 6 of the toggle member is preferably provided with a countersunk portion 8 on each side of which is a slot 8'. Below the channel 6 is the other part of the toggle member which may be in the form of a sheet metal channel 9 from the sides of which project ears 10 adapted to extend thru the slots 8' as shown in Fig-

ures 1 and 2. The ears 10 are perforated, and a rivet pin 15 extending thru these perforations serves to connect the toggle members to the end of a chain composed of links 16 connected by rivet pins 17. As shown, one end of the rivet pin 15 and one end of some of the rivet pins 17 are split and spread for reasons hereinafter explained. The other end of the chain is adapted to be secured by a swivel connection to the threaded stem of the instrument 18, with which the radiator cap 19 may be equipped. This swivel connection may comprise a drawn metal shell 21 having an enlarged end provided externally with knurling, within which is secured a ring 22 provided with internal threads adapted to engage with the threaded stem of the instrument 18. In a threaded hole in the shell 21 and the ring 22 is a set screw 23 which may be provided with a polygonal wrench socket 70 adapted to receive a wrench which permits the set screw to be forced into engagement with the threaded stem of the instrument 18. After the set screw 23 has been screwed into its holding position, the socket 24 therein can 80 be filled with a lead shot 24' which can be readily forced in and will be exceedingly difficult to remove to thus prevent unauthorized removal of the screw 23. The sides of the shell 21 are provided with holes 25 which 85 prevent the sleeve from interfering with the function of the temperature indicating instrument. The bottom of the shell 21 is flanged or provided with a hole through which extend the shanks of link members 28 90 having ends which extend through and are riveted above a disk 29 which is adapted to rest on the flange in the bottom of the shell 21 and is not small enough to pass through the hole therein. By thus connecting the chain 95 13 to the shell 21, a swivel connection between the sleeve and the chain 13 is provided.

In order to make it practically impossible for a thief to cut the chain with ordinary tools, the upper portion of the chain, which extends above the top of the radiator stem when the cap is removed, is preferably provided with links 30 and 31 which may be heavier than the other chain links 16, and may be of the form shown in Figures 1, 2 and 3.

In Figure 3 is shown a portion of an automobile radiator 35 provided with the usual neck 36 through which the radiator may be filled, and with which the radiator cap 19 makes threaded connection. The radiator 35

is shown as equipped with a baffle plate 38 of a kind now provided in many radiators.

The method of installing the retaining device shown in Figures 1 to 5 is as follows: 5 Measure the inside height of the radiator neck 36, add $\frac{1}{4}$ inch to this measurement and lay off this total distance along the chain from the bottom of the shell 21. Remove the split-ended rivet pin 17 nearest this measurement, and also the split-ended rivet pin 15, and discard the chain links 16 between these rivet pins. Then re-attach the toggle member 9 to the chain by inserting the rivet pin 15 in the hole of the free end of last link 10 of said chain. The split ends of the rivet pin 15 and any rivet pins 17 which have been left in the chain should then be spread and hammered out to form permanent rivet heads. The toggle, with the member 6 in the 15 bent condition shown in Figure 2, is then dropped into the radiator neck 36, care being taken to keep hold of the shell 21 preferably by means of a string or wire. Different radiators vary as to the diameter and lengths of 20 their necks and as to the location of the baffle plates, and where the device is used in connection with some radiators it may be necessary to break off either one or both of the ends 6' of the toggle member 6 in order to be able to 25 work the toggle member into the space in the top of the radiator. In some instances, it may even be necessary to discard entirely the toggle member 6 and use merely the toggle member 9. The bent condition of the toggle member 6, however, facilitates its insertion 30 into the space in the radiator above the baffle plate 38, and then into a position in which both ends of the toggle member 6 will be beneath the top of the radiator. After the toggle member has been inserted in the space in 35 the top of the radiator, the shell 21 is screwed onto the stem of the instrument 18, and the set screw 23 is screwed in against the threads on the instrument stem so as to prevent unscrewing of the sleeve, after which the wrench socket 24 in the set screw 23 can be plugged with a shot 24' as mentioned above. By then pulling upwardly on the radiator cap, the toggle member 6 can be straightened from 40 the curved or bent condition shown in Figure 2 to the straight condition shown in Figure 3 to thus distend it, or in other words increase its length, and the installation of the fastening device is complete. If necessary, of course the chain can be pulled so as to 45 straighten out the toggle member before attaching the sleeve to the instrument stem.

In the form of retaining device shown, it is possible to make the length of the chain 50 between the toggle member and the shell 21 of such a length that the instrument 18 and the cap 19 can be tipped over the edge of the radiator neck so that the cap will not interfere with the filling operation; and at the 55 same time the chain may be of such a length

in relation to the length of the toggle member 10 and dimensions of the radiator neck, that even when the radiator cap is in place on the radiator neck the toggle member cannot move to a position which would permit of its withdrawal through the radiator neck. With this form of retaining device, therefore, it is virtually impossible to remove it from a radiator without first either disconnecting it from the instrument or bending the toggle member 10 back to the position shown in Figure 2, or performing both of these operations, each of which is difficult and requires considerable time and skill. In fact, bending back of the toggle member after it has been 60 inserted in the radiator is in most instances practically impossible.

While I have shown a certain form in which my invention may be embodied, it is to be understood that in the appended claims I intend to cover not only this form but any other forms which embody the principles of my invention.

What I claim is:

1. A retaining device adapted for use with a radiator cap equipped with an instrument having a stem projecting through a hole in said cap, comprising a connection adapted to be secured to the instrument stem, a chain attached to said connection, and a toggle member attached to said chain, said toggle member being in two parts one of which is capable of being bent and the other of which has ears projecting through the first mentioned part and attached to said chain. 100

2. A retaining device for a radiator cap to prevent severance of the cap from the radiator, but constructed to allow sufficient movement of the cap to enable the radiator to be filled through the neck, said device comprising an anchor within the radiator and a connector joining the anchor and the cap, said connector having a section at its upper end more resistant to severance than the remainder of the connector, and being adjusted to an effective length such that only said more resistant section may be withdrawn from the radiator neck to an accessible position. 105

3. A retaining device for use with a radiator cap equipped with an instrument having a threaded stem projecting through a hole in said cap, comprising a shell which at one end is enlarged, a ring secured within the enlarged end of said shell and provided internally with threads adapted to cooperate with the threaded stem of the instrument, means for locking said shell and ring to the instrument stem, a toggle member, and a connection between said shell and said toggle member. 115

4. A retaining device for use with a radiator cap equipped with an instrument having a threaded stem projecting through a hole in said cap, comprising a drawn metal shell having a threaded ring secured therein, said shell 130

having a shoulder upon which the ring is seated and being flanged at its lower end, a toggle member, and a swivel connection between the flanged end of said shell and said 5 toggle member.

5. The method of installing a theft proof retaining device for a cap equipped with an instrument for the radiator of an automobile which consists in determining the proper 10 length of a chain connecting member required between the cap and the retaining device according to the length of the radiator neck, to prevent meddling with the retaining device, and adjusting the number of links in said 15 chain according to the length so determined, then attaching the retaining element to the chain, then passing the retaining element thru the neck, then fastening the cap to the connecting member, and then distending the 20 retaining device within the radiator.

6. A retaining device for a cap to close the neck of an automobile radiator, said device comprising a retaining element, and a chain connector between said cap and said retaining element, said chain being composed 25 of links connected to each other by rivets, some of the rivets being split at one end to enable their removal and the removal of some of the links to shorten the connector according 30 to the length of said neck.

7. A retaining device for a cap to close the neck of an automobile radiator, said device comprising a retaining element and a connector between said cap and said retaining element, said retaining element being collapsible to facilitate passage thru the neck of the radiator and distendable after it is placed within the radiator, said retaining element being also effective to be shortened independently of its collapsibility according to 35 the diameter of the neck.

8. A retaining device for a cap to close the neck of an automobile radiator, said device comprising a retaining element and a connector between said cap and said retaining element, said retaining element being collapsible to facilitate passage thru the neck of the radiator and distendable after it is placed within the radiator, said retaining element being provided with ends so constructed as to facilitate shortening of said retaining element according to the diameter of the neck. 50

9. A retaining device for a cap to close the

neck of an automobile radiator, said device comprising a retaining element and a connector between said cap and said retaining element, said retaining element being collapsible to facilitate passage thru the neck 55 of the radiator and distendable after it is placed within the radiator and removable ends on said retaining element to shorten it.

10. A retaining device for a cap to close the neck of an automobile radiator, said device comprising a retaining element, a supporting bar for said retaining element, and a connector between the supporting bar and said cap, said retaining element having a slot, and an ear on said supporting element, said ear extending thru said slot and being connected to said connector. 60

11. A retaining device for a cap to close the neck of an automobile radiator, said device comprising a retaining element, said retaining element having a slot, a connector, said connector having a bar connected at its end 70 to support the retaining element, said retaining element being collapsible to facilitate passage thru said neck into the radiator, said bar being effective to assist in distending the retaining element by bending it back to 75 straighten it, said bar being also effective to resist further bending of said retaining element when it has been straightened.

12. A retaining device for a radiator cap to prevent removal of the cap from the radiator constructed to allow sufficient movement of the cap to enable the radiator to be filled through the neck, said device comprising an anchor within the radiator and a connector joining the anchor and the cap, comprising a 85 chain having the upper portion thereof highly resistant to severance and permanently connected to the lower portion thereof, said 90 lower portion of the chain consisting of links less resistant to severance than the upper portion of the chain, and means detachably securing such links together so that the length of the chain can be adjusted before application to a radiator, the effective length of the 95 chain being so adjusted that access to the less resistant links and the connecting means therefor cannot be had when the device is applied to a radiator. 100

In testimony whereof I have affixed my signature to this specification.

HERMAN SCHLAICH.
